UNITED STATES PATENT OFFICE.

SILAS O. ROREM, OF SIOUX CITY, IOWA.

KEY-DUPLICATING MACHINE.

1,381,747.

Specification of Letters Patent. Patented June 14, 1921.

Application filed April 9, 1920. Serial No. 372,727.

To all whom it may concern:

Be it known that I, SILAS O. ROREM, a citizen of the United States, and a resident of Sioux City, in the county of Woodbury and State of Iowa, have invented new and useful Improvements in Key-Duplicating Machines, of which the following is a specification.

The present invention is a key duplicating machine, the principal object being to provide a machine wherein notches may be cut in a key blank at points coincident with the notches of an original or pattern key and which will cut the notches the same 15 depth and width as the notches in the pattern key.

Another important object of the invention resides in the provision of a key duplicating machine wherein the pattern key and 20 key blank are held in parallel relation and in transverse alinement with each other so that the blank will be cut or notched at points coincident with the notches in the pattern key.

25 Further, it is the purpose of the invention to provide a machine which after the pattern key and key blank have been arranged in coinciding relation it will be unnecessary to disturb either the key or blank 30 in order to successively cut the blank at different points along its edge, but that the machine is so constructed as to permit the blank and pattern key to be advanced across a cutter prior to each cutting operation.

35 The invention also comprehends a rotat- ing cutter and a gage so arranged with respect to the cutter as to cut notches in the key blank of the same dimensions as the notches in a pattern or original key.

40 Another object of the invention resides in the provision of a key duplicating machine which may be driven either by hand or motor, which is simple in construction, consists of few parts that are easily assem- 45 bled and disassembled, and which may be manufactured and sold at a minimum cost.

With these and other objects and advan- 50 tages in kind, the invention includes the combination of elements, constructions and arrangements of parts, operations and spe- 55 cific features, all of which will be herein- after enlarged upon and explicitly defined in the subjoined claims.

On the drawings, 55 Figure 1 is a side elevation of a key du-

plicating machine constructed in accordance with my invention;

Fig. 2 is a rear end elevation of the same;

Fig. 3 is a vertical sectional view of the 60 machine;

Fig. 4 is a front end elevation thereof;

Fig. 5 is a perspective of the movable car-

riage embodied in the invention;

Fig. 6 is a perspective of the horizontally 65 and longitudinally movable plate included

in the invention;

Fig. 7 is a vertical sectional view taken

on line 7—7 of Fig. 3;

Fig. 8 is a horizontal sectional view taken 70

on line 8—8 of Fig. 3;

Fig. 9 is a perspective of the pattern key

and key blank holding plate; and

Fig. 10 is a perspective of the gage blade

75

Referring in detail to the drawing, wherein like characters of reference designate cor- 80 responding parts throughout the several views, the numeral 5 designates the base of the machine which is provided with beveled parallel walls 6 at its longitudinal edges. The inner face of the beveled edges of the walls 6 are cut away to afford parallel lon- 85 gitudinally inclined guideways 7.

Movable longitudinally of the base 5 is a 85 carriage or slide 8 provided with parallel in- clined sills upon its under face and at its longitudinal edges which are slidably re- 90 ceived in the inclined guideways 7. The outer faces of the sills 9 are cut away at their lower edges in mating relation to the beveled edges of the walls 6 as indicated at 10 while their under faces are inclined in the same plane as the guideways 7. The upper face of the slide 8 is provided with upstanding 95 longitudinal guides 11 at its longitudinal edges and slidably mounted upon this upper face is a plate 12 provided with parallel tongues 13 resting upon the upper face of the slide and abutting the guides 11 which 100 retain the plate against lateral movement during the longitudinal adjustment of the plate.

Movable with the plate 12 and also adapt- 105 ed for adjustment transversely of this plate is a key holding plate 14 formed with trans- versely arranged stepped parallel tongues at its opposite ends which are received in transverse stepped guideways or rabbets 15 formed in the upper face of the plate 12. 110

The upper face of the plate 14 is provided with transverse key receiving recesses 16 and 16^a at its opposite ends, the latter recess accommodating the pattern key while the former retains the key blank to be duplicated. Plates 17 are secured to the opposite ends of the plate 14 between which plates and the opposite wall of each of the recesses the key and blank are positioned. In order to position the key and blank in alignment so that the blank will be notched or cut at a point in alignment with the notch in the pattern key an indicating mark 14' is inscribed in the plate 14 adjacent each of the recesses 15 and are disposed in alignment with each other and with which the ends of the blank and key coincide when the latter are properly positioned.

In order to move the carriage 8 up and down the inclined ways and to move the plate 12 relative to the carriage handles 19 and 21 are attached to the inner ends of these members. Likewise, a handle 18 is provided for the plate 14 for moving the same transversely of the plate 12.

Extending from the inclined walls 6 are pairs of uprights 22 to the upper ends of which parallel horizontal bars 23 are connected. A shaft 24 is journaled at the outer ends of the bars 23 and fixed on this shaft is a circular knife 25. A pulley 26 is fixed to one end of the shaft 24 and passing around this pulley is a drive belt 27 which is driven by a relatively large drive wheel 28 supported upon a stub-shaft 29 extending laterally from one of the uprights 22 at the inner end of the base. This drive wheel 28 has a drive pulley 30 fixed thereto about which a drive belt 31 is engaged which may be driven by any source of power (not shown).

Supported in the horizontal bars 23 at a point between the rotary knife 25 and the stub-shaft 29 is a rod or shaft 32 upon which a sleeve 33 is mounted for longitudinal adjustment and is retained in adjusted position through the medium of set-screws or other fastenings 34. The sleeve 33 is formed with a downwardly disposed extension 35 at one end thereof and to which extension a horizontally disposed gage blade 36 is attached and that extends parallel to the rotary knife and in longitudinal alignment therewith.

Assuming that the parts of the machine are in the position illustrated in Fig. 1 and the pattern key and key blank arranged as indicated in dotted lines, the horizontally and longitudinally movable plate 12 is drawn toward the operator until the key blank is disposed forwardly of the rotary knife. The carriage 8 is now drawn up the inclined trackways until the lower longitudinal edge of the gage blade engages the lower or horizontal wall of the notch in the pattern key and holding the carriage in this elevated position the plate 12 is now pushed forwardly,

carrying the key blank in the path of the rotating knife. Should not the initial operation be sufficient to cut the notch wide enough the key holding plate is moved transversely of the longitudinally movable plate 12 and this plate is then drawn toward the operator to again advance the key blank in the path of the rotating cutter. In order to cut successive notches in the key blank the carriage is pushed down the inclined trackways after each cutting operation and the key holding plate then adjusted transversely and the carriage and plate operated in the above manner.

It is to be understood that the form of my invention herewith shown and described is to be taken as a preferred example of the same, and that various changes in the shape, size and arrangement of parts may be resorted to without departing from the spirit of the invention or the scope of the subjoined claims.

Having thus described my invention, what I claim as new and desire to secure and protect by Letters Patent of the United States is:

1. In a key duplicating machine, a base provided with inclined trackways, a carriage movable in the inclined trackways, a plate longitudinally movable upon the carriage, means for retaining a key and key blank in parallel spaced relation, said means being capable of adjustment transversely of the plate, a rotary cutter supported above the plate, a gage blade arranged in advance of the cutter, the carriage being adapted to be moved up the inclined trackways until the gage blade engages the bottom wall of one of the notches in the pattern key, whereupon advancing the horizontal and longitudinally movable plate the blank will be cut to the same depth as the depth of the notches in the pattern key.

2. In a key duplicating machine, a base, inclined trackways disposed longitudinally of the base, a carriage, parallel inclined sills disposed upon the under face of the carriage and disposed in the trackways, a handle for shifting the carriage, a plate supported on the upper face of the carriage and longitudinally adjustable thereon, means for supporting a pattern key and key blank edgewise and in spaced parallel relation, a rotary cutter supported above the plate, and means for limiting the upward movement of the carriage and inclined trackways after the same has been moved to a point where the key blank will be cut to a depth corresponding to the depth of the cut in the pattern key upon advancing the plate toward the cutter.

3. In a key duplicating machine, a base provided with inclined parallel trackways, pairs of parallel uprights extending from the base, a horizontal bar connected with

- each pair of uprights, a shaft journaled in the outer ends of the bars, a cutter fixed to rotate therewith, a drive wheel supported on one of the uprights, a driving element 5 operatively connecting the drive wheel and shaft, a gage blade supported between the horizontal bars and extending longitudinally of the base, a carriage movable in the inclined trackways, a plate mounted on the 10 carriage for longitudinal movement in a horizontal plane, means on the plate for retaining a pattern key and key blank in spaced parallel relation and coincident to each other, the carriage being adapted to be 15 moved toward the higher end of the trackways until the gage blade engages the lower wall of the notch in the key and held in such position while the plate is advanced toward the cutter.
- 20 4. In a key duplicating machine, an inclined base, a carriage slidably mounted thereon, means on the carriage for supporting a key and key blank in transverse alignment and capable of both longitudinal and 25 transverse adjustment, a rotary cutter supported above the carriage at the lower end of the base, a gage blade disposed in advance of the cutter and adapted to engage any one of the notches in the key upon the 30 ascent of the carriage, whereupon advancing the key and blank holding means toward the cutter the latter will be cut the same depth as the notches of the key and in coinciding relation thereto.
- 35 5. In a key duplicating machine, a base, inclined parallel trackways, a carriage slidably mounted in the trackways, a rotary cutter supported above the carriage, drive means supported on the base for driving the 40 cutter, a gage blade extending longitudinally of the base and arranged in advance of the cutter, a plate mounted upon the upper face of the carriage and capable of movement longitudinally of the same, a key and blank 45 holding plate mounted on the first mentioned plate and adapted for movement transversely of the same, the carriage being adapted to be moved toward the highest end of the trackways until the gage blade engages the lower wall of a notch in the key whereupon 50 advancing the first mentioned plate toward the cutter the blank will be cut coincident with the notch in which the gage blade is engaged.
6. In a key duplicating machine, a base, 55 inclined trackways arranged on the base, a carriage slidably mounted in the trackways, a plate longitudinally movable on the carriage, means on the plate for retaining a key and key blank in coinciding relation at 60 opposite ends of the plate, a rotary cutter supported above the carriage and disposed above the base at the lower end of the trackways, a gage blade supported in advance of the cutter and capable of adjustment transversely of the blade, the gage blade being adapted to enter one of the notches in the key upon movement of the carriage toward the highest end of the trackways whereby 65 the plate will be disposed at such a height as to cause the blank key to be cut at a depth equal to the depth of the notch in the key upon advancing the plate to the cutter.
7. In a machine of the character described, 70 a base, inclined trackways on the base, uprights extending from the base, cross bars connecting each pair of uprights, a cutter supported between the cross bars, a rod supported in the cross bars in advance of the cutter, a sleeve adjustable on the rod, a gage 75 blade carried by the sleeve and extending longitudinally of the base, a carriage slidably mounted in the guides, a plate slidably mounted on the carriage, a key retaining 80 plate slidable transversely of the first mentioned plate and provided with parallel grooves to accommodate a pattern key and blank key respectively, the gage entering one 85 of the notches in the pattern key to dispose the first mentioned plate at the proper elevation upon movement of the carriage toward the highest end of the inclined trackways.

SILAS O. ROREM.
